UNITED STATES PATENT OFFICE.

GEORGE H. BURROWS, OF SOMERVILLE, ASSIGNOR, BY MESNE ASSIGNMENTS, TO HIMSELF AND E. GILMAN COLBY, OF GREENWOOD, MASS.

APPARATUS FOR BURNING GAS.

SPECIFICATION forming part of Letters Patent No. 267,971, dated November 21, 1882.

Application filed April 3, 1882. (No model.)

To all whom it may concern:

Be it known that I, GEORGE H. BURROWS, of Somerville, in the county of Middlesex, of the State of Massachusetts, have invented a new and useful improvement in Means or Apparatus for Burning Gas for the Illumination or Heating of Objects; and I do hereby declare the same to be described in the following specification and represented in the accompanying 10 drawings, of which—

Figure 1 is a top view, Fig. 2 a front elevation, and Fig. 3 a vertical and transverse section, of an apparatus embracing my invention, the nature of which is defined in the claims 15 hereinafter made.

In the said drawings, A A A A denote a series of gas-burners arranged around a gas-heater, B, and communicating with the lower part of such. This gas-heater consists of a cylindrical and tubular standard, a, surmounted by a hollow globe, b, and having within it an induct, c, to extend from the bottom d of the standard up nearly to the top of the chamber or space within the globe. The standard is 20 provided at its lower end with a female screw, e, to secure it upon a gas-pipe, so as to enable gas therefrom to pass into the induct c, and from thence upward into the hollow globe and down within the standard to and into each of 25 the burners. The globe should be arranged at a height which will insure it being heated to the best advantage by heat radiated from the inner surfaces of the flames of the jets of the burners. The gas in flowing into and down 30 within the heater B becomes very highly raised with the temperature, so that on being discharged from the jets its combustion becomes much easier or greatly facilitated and improved, the carbon of the gas being almost if not entirely 35 consumed, and in consequence thereof the flame 40 is rendered brighter in color and possessive of increased light-giving properties. Furthermore, in a very short time after inflaming the gas at the burners the heater becomes so highly 45 raised in temperature that should the flame of any one of the burners be suddenly extinguished by a current of air the effluent heated gas from such burner will generally be at once rekindled or inflamed by the heater.

50 The globe of the heater, on its external sur-

face, I usually make light-reflecting like a mirror. To accomplish this, when the body of the heater is brass or iron, I nickel-plate it on the outer surface of the globe especially, if not on the entire outer surface of the heater, and I 55 brightly polish the metallic covering. In this case the heater is made not only to perform the function of absorbing heat radiated from the flames of the burners, but of reflecting or dispersing in directions radial to its globe the rays 60 of light proceeding from the inner sides of the flames of the burners.

A compound gas heater and burner as above described can be employed to great advantage and with highly economical results in producing 65 light from illuminating-gas.

By encompassing each of the burners with a conical sleeve to direct air to the flame the heating power of the flames will be increased, though at the expense of their illuminating 70 powers, in which case the apparatus can be used to advantage as a heater.

I am aware of the gas heater and burners as shown and described in the United States Patents numbered 249,063 and 251,102, in each of 75 which the gas enters at the top of the heater and passes downward through the said heater, and thence downward out of such by a pipe or pipes before reaching the burner or burners; but in my apparatus the gas enters by an induct extending upward within the heater from 80 its bottom, and thence passes downward within the heater to the burners, the heater being entirely closed at top. Therefore with my apparatus there is no pipe extending above the 85 heater in a manner to intercept the light, and thereby cause shadow; and, besides, my heater in its upper part is a hollow globe, or substantially such, and has its outer surface light-reflecting, to disperse in all directions radially 90 from it, and particularly from its upper part, the rays of light that may fall on it from the flames of the burners.

I would further remark that my burner differs very materially from either of those shown 95 in S. Andrews' patent, dated April 15, 1831, and in the United States Patents numbered 26,888 and 253,003, in which the gas-jets are arranged to produce a continuous and practically circular or tubular flame, which, by encompass- 100

ing the heater, prevents light from being reflected therefrom, as it is by the globular part of my heater; and, besides, the heaters of such patents are not reflectors, as is that of my above-
5 described burner. In my invention the gas-burners are separate from each other and arranged at intervals apart, so as to enable reflected light to pass between them and their flames, the rays of light being reflected upward
10 as well as downward by the globular reflector of the heater. Such burners also have their tips or upper ends placed in or near the central horizontal plane of the globular reflector.

I would further state that I do not confine
15 my invention to four burners, as shown, as any other suitable number of them may be used with the heater.

What I claim as my invention is as follows, *viz.*:

20 1. The improved compound gas heater and burner constructed substantially as described—*viz.*, with the heater closed at top and with the gas-induct to extend upward within the heater from its bottom nearly to its top, in combination with a series of separate gas-burners arranged about the heater and with intervals or
25 spaces between them, as shown, to lead or open out of its lower part, and having their tips or

upper ends placed in or near the central horizontal plane of the globular reflector, all es- 30 sentially as set forth.

2. The described compound gas heater, burner, and light-reflector, consisting of the gas-heater, having a light-reflecting outer surface, and the induct and series of separate gas-burners arranged with and applied to such heater and having their tips or upper ends placed in or near the central horizontal plane of the globular reflector, substantially as set forth. 40

3. The combination of the gas-heater globular in its upper part, such part having a light-reflecting outer surface, with the gas-induct arranged to extend upward within such heater, and with a series of separate gas-burners arranged around the heater and apart from each other and leading out of its lower part, and having their tips or upper ends placed in or near the central horizontal plane of the globular reflector, all being substantially as set 45 50 forth.

GEORGE H. BURROWS.
